US00D714278S

(12) **United States Design Patent**
Case et al.(10) **Patent No.:** US D714,278 S
(45) **Date of Patent:** ** Sep. 30, 2014(54) **MOBILE PHONE CASE**(71) Applicant: **Nite Ize, Inc.**, Boulder, CO (US)(72) Inventors: **Richard N. Case**, Boulder, CO (US);
Gregory M. Adelman, Boulder, CO
(US)(73) Assignee: **Nite Ize, Inc.**, Boulder, CO (US)(**) Term: **14 Years**(21) Appl. No.: **29/461,939**(22) Filed: **Jul. 29, 2013**(51) LOC (10) Cl. **14-03**
